(57) **CLAIM**

The ornamental design for a shaped burp cloth, as shown and described.

DESCRIPTION

FIG. 1 is a front perspective view of the shaped burp cloth shown in use.

FIG. 2 is a side perspective view of the shaped burp cloth shown in use.

FIG. 3 is a front perspective view of the shaped burp cloth shown in use.

FIG. 4 is a rear perspective view of the shaped burp cloth shown in use.

FIG. 5 is a front elevation view of the shaped burp cloth.

FIG. 6 is a rear elevation view of the shaped burp cloth.

FIG. 7 is a left side elevation view of the shaped burp cloth.

FIG. 8 is a right side elevation view of the shaped burp cloth.

FIG. 9 is a top plan view of the shaped burp cloth; and,

FIG. 10 is a bottom plan view of the shaped burp cloth.

Broken lines in the drawings are included for the purpose of illustrating an environment and form no part of the claimed design. The claimed invention can be used in other environments.

1 Claim, 4 Drawing Sheets
